UNITED STATES PATENT OFFICE

2,032,985

INTERNAL COMBUSTION ENGINE

William Haul, St. Louis, Mo.

Application October 31, 1933, Serial No. 696,103

1 Claim. (Cl. 123—65)

This invention appertains to new and useful improvements in internal combustion engines, and more particularly to an engine of the two cycle type.

5 The principal object of the present invention is to provide an internal combustion engine in which the valves are simplified and wherein the explosion chamber is scavenged thoroughly and quickly.

10 During the course of the following specification and claim, various important objects and advantages of the invention will become apparent to the reader.

In the drawings:—

15 Figure 1 represents a side elevational view of the engine.

Figure 2 represents a top plan view of the engine.

20 Figure 3 represents a vertical sectional view through the engine.

Figure 4 represents a horizontal sectional view taken substantially on line 4—4 of Figure 3.

Figure 5 represents a sectional view taken substantially on line 5—5 of Figure 3.

25 Figure 6 represents a side elevational view of the combined piston and valve.

Figure 7 represents a top plan view of the cylinder and valve combination.

Figure 8 represents a top plan view of the engine with the head removed.

Figure 9 represents a sectional view taken substantially on line 9—9 of Figure 3.

Figure 10 represents a horizontal sectional view taken substantially on line 10—10 of Figure 3.

35 Referring to the drawings wherein numerals designate like parts, it can be seen that numeral 5 represents a two-cylinder block having a water jacket 6. Below this is located a crank case 7 through which the crank shaft 8 extends. Num- 30

meral 9 represents the head which is hollow to accommodate water of the cooling system, and extending vertically through the head 9 are the barrels 10 to accommodate the valve sleeves 11 on the pistons 12 which operate in the cylinders 13.

45 Each of the tubular valves 11 extends upwardly from the central portion of the piston head and is partitioned off just above the piston 12, as at 13, so that the fuel supply is entirely cut off when the partition is in the position as shown in Figure 3 above the engine head. The fuel is compressed in the valve 11 on the up stroke of the piston and when the piston is at the lower portion of its power stroke, fuel is admitted to the valve 11. The valve sleeve 11 50 is provided with perforations 14 in the side there-

of just above the partition 13, and with an inlet port 11a adjacent its upper end, while depending into the valve sleeve 11 is the tubular core 15 which is flanged at its upper end and secured by bolts 16 to the upper portion of the head 9. Between the upper end of the core 15 and the upper end of the valve sleeve 11 is a lubricant pocket 17.

5 Numerals 18 represent a fuel duct leading through the head for each of the valves 11 and 10 each of these fuel ducts opens through the inner face of the corresponding barrel 10. Within each of the explosion chambers 19 are the points of a spark plug 20. The piston 12 is hollow and has oil drain openings 21 therein at 15 its lower portion, as shown in Figure 3. The piston 12 is provided with a small cylindrical skirt 22 which operates within the tubular guide 23 depending from the cylinder block 5. The space between the cylinder bore and the apron 22 defines an air chamber 24. Each of the cylinders has an air intake line 25 with an outwardly closing check valve 26 therein. Each of these air lines 25 opens into the corresponding air chamber 24 below the piston and by means of these 20 air lines 26, a duct 27 extends upwardly to communicate with the cylinder at a point adjacent the upper end of the cylinder and a point which is never below the lower portion of the piston 12.

25 As is clearly shown in Figure 3, these ducts 27 are connected by a pipe 28.

The pistons 12 are connected by a connecting rod 29 to the crank 30 of the shaft 8. Numeral 31 denotes an exhaust opening for each of the cylinders and is substantially on the same horizontal plane as the upper openings of the ducts 27.

35 In the operation of the engine, it can be seen in Figure 3 that the piston 12 is starting downwardly on its explosion stroke. As the piston 40 moves downwardly, air is being compressed in the chamber 24 and it will be noted that this air cannot escape due to the fact that the duct 27 is closed by the piston 12 and the air inlet 25 is closed by the check valve 26. When the 45 piston moves to its lowermost position, the upper end of the duct 27 is exposed so that the compressed air sweeps across the explosion chamber and scavenges the cylinder by way of the exhaust port 31. Immediately subsequent to 50 this, the port 11a in registering with the inlet port 18 will permit fuel to pass downwardly through the sleeve 11 by way of the opening 14 to the explosion chamber, and as the piston moves upwardly, the fuel inlet will be closed and 55

the gas caught in the explosion chamber will be compressed by the uprising of the piston. At the same time, the piston 12 is creating a suction in the chamber 24 which sucks air through the check valve 26, and when the compressed fuel is ignited, the same operation repeats itself.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

15 In an internal combustion engine, a cylinder, a piston operative in the cylinder, a cylinder head, said cylinder head provided with a barrel

extending vertically thereon, a valve sleeve extending upwardly from the piston and into the barrel, said valve sleeve having a partition therein extending transversely thereof and openings in the sleeve above the partition, a fuel inlet in the said head communicating with said barrel, and a closure secured to the said barrel and provided with a tubular member depending therefrom protruding into the upper portion of the valve sleeve, said valve sleeve being provided with 10 a fuel inlet port in the upper end portion thereof registerable with the fuel inlet in the head when the piston reaches its lowermost position, said depending member and barrel defining a snug guide for the valve sleeve.

15 WILLIAM HAUL.
